DESIGN FOR A SHOE OR SIMILAR ARTICLE

Kenneth Keyes, New York, N. Y.

Application October 21, 1943, Serial No. 111,440

Term of patent 7 years

To all whom it may concern:

Be it known that I, Kenneth Keyes, a citizen of the United States of America, residing in New York city, county of New York, and State of New York, have invented a new, original, and ornamental Design for a Shoe or Similar Article, of which the following is a specification, reference being had to the accompanying drawing, forming part thereof.

The figure on the drawing is a perspective view of a shoe or similar article showing my new design. The opposite side presents substantially the same appearance as the side shown on the drawing.

I claim:

The ornamental design for a shoe or similar article, substantially as shown and described.

KENNETH KEYES.
